UNITED STATES PATENT OFFICE.

JOSEPH MARIE ETIENNE FRANC, OF ST. VALLIER, FRANCE.

WASHING, RINSING, AND WRINGING MACHINE.

1,312,393.

Specification of Letters Patent.

Patented Aug. 5, 1919.

Application filed February 15, 1918. Serial No. 217,416.

To all whom it may concern:

Be it known that I, JOSEPH MARIE ETIENNE FRANC, engineer, of St. Vallier, Drôme, France, a citizen of the French Republic, have invented a certain new and useful Improved Washing, Rinsing, and Wringing Machine, of which the following is a specification.

The object of this invention is to unite in a single device apparatus for performing the three operations of washing, rinsing and wringing articles of clothing.

In the annexed drawings Figure 1 is a vertical section of the operative part of the improved machine in position for washing and rinsing,

Fig. 2 is a similar section in the position of wringing,

Fig. 3 is a cross-section on line 3—3 of Fig. 1.

The machine comprises a hollow cylinder *a* constructed of wood or of non-oxidizable metal provided with two hollow trunnions *b* *b*¹ turning in bearings *c* *c*¹ on a suitable frame. The one trunnion *b* carries a pinion *d* to be driven by a chain or worm by means of a hand crank or motor so as to rotate the cylinder on its axis.

In the cylinder *a* is a plunger *e* movable along the whole length of the cylinder. A screw shaft *f* engaged in the trunnion *b* which is screw threaded for the purpose, effects the translatory movement of the plunger *e*, the said shaft being rotatable by means of a handle arranged on its squared end *g*.

The screw shaft *f* is hollow and has adjacent its piston openings *h* through which the water or washing solution conveyed through the shaft is introduced into the cylinder.

The second trunnion *b*¹ is also hollow and serves for the outlet of the liquid, it is provided with a perforated plate *i* preventing the passing out of the linen or other articles. 45 A removable plug *b*² closes the passage in the trunnion *b*¹ during the washing operation.

The linen or other articles of clothing are introduced into the machine through an 50 opening closed by a door *j*.

The washing and rinsing is effected by rotating the cylinder. Ribs *k* are arranged along the walls of the cylinder and stir the linen and cause it to roll on itself effecting 55 complete and uniform penetration by the liquid employed and causing thorough washing or rinsing as the cylinder revolves.

For wringing the cylinder is maintained stationary but the piston *e* is pushed inward 60 by means of the screw shaft *f* so as to expel the water through the trunnion *b*¹.

What I claim as my invention and desire to secure by Letters Patent of the United States is:—

A combined washing, rinsing and wringing machine comprising in combination a rotary imperforate cylinder having hollow trunnions, one of which is internally screw-threaded, bearings for said trunnions, a hollow screw shaft traversing said screw threaded trunnion, an imperforate piston carried by said screw shaft movable longitudinally in said cylinder and means for rotating said cylinder. 75

In witness whereof I have signed this specification in the presence of two witnesses.

JOSEPH MARIE ETIENNE FRANC.
